Attorney

UNITED STATES PATENT OFFICE

LUDWIG FÖBUS, OF DORTMUND-BAROP, GERMANY

COOLING MEANS FOR CASTINGS

Application filed December 24, 1929, Serial No. 416,232, and in Germany January 2, 1929.

This invention refers to the art of cooling castings and the like and in particular of steel castings and it is intended to facilitate the casting operation and to obtain a more uniform, gradual and thorough cooling action than it is possible with most of the means heretofore suggested, and it is a further object of the invention to greatly simplify and cheapen the construction and manufacture 10 of casting means for the purpose referred to. The invention among other uses and advantages is particularly adapted for the cooling of steel castings in which the masses are unevenly distributed, and when employed in 15 this connection, it will prevent the occurrence of injurious tensional strains in the castings during the cooling procedure.

As compared with cooling bodies for the purposes mentioned, as disclosed by the previous art, and comprising mostly bodies of wire adapted to be bent into any suitable form and configuration, the cooling bodies according to this invention are particularly distinguished by the fact that they are made 25 of sheet metal by a punching, stamping or similar process and by bending them into the desired shape. Thus, the method of manufacture is very considerably simplified and cheapened; furthermore than that, in view 30 of the easy and ready shaping of the cooling body obtained by the punching and bending operations a perfectly uniform cooling action may be obtained. There is the further advantage that the cooling bodies of the invention may be easily moulded, so as to assume angularly bent or curved shapes, to thereby adapt them to the particular configuration of the casting to be treated. Broadly considered, the cooling body of the invention 35 has the shape of a rather ramified structure by punching out a substantially oblong strip of sheet metal which is provided with lateral flaps or projections obtained by incisions or indentations and alternately bent 40 upon opposite sides of the structure, similar to what has already been suggested in connection with supports for foundry cores. The said flaps or extensions may be of different lengths.

50 The invention will be more fully described

by reference to the accompanying drawings, showing exemplifications of the subject matter of the invention. Figure 1 is a side view of the cooling body; Figure 2 is a top plan view of Figure 1, and Figure 3 is a front view 55 at right angle with relation to Figure 1—Figure 4 illustrates the flatly spread out cooling body according to Figures 1 and 2, and Figure 5 is a plan view of a modified construction of the cooling body.—Figure 6 is a 60 lateral view of another form of embodiment, showing a longitudinally extending cooling body.

The cooling bodies are cut out or punched out from sheet metal of suitable thickness; 65 preferably a fundamental blank or structure in accordance with Figure 4 may be employed, constituting substantially a longitudinal or oblong strip of sheet metal at the longitudinal sides of which substantially 70 rectangular recesses *a* are cut out which are staggeringly or alternatingly arranged, so as to form projecting tongues *b* on opposite longitudinal sides. At the edges of these projections or tongues *b* the cooling body is 75 provided with straight incisions, so as to allow of the flaps or tongues *b* and the intermediate sections *d* to be bent out of the plane of the strip of metal. At its lower end the metal strip shows a pointed extremity cut 80 out from the body of the strip at *f* by means of which the cooling body is inserted in the moulding sand. Figures 1 and 3 show the final shape of the cooling body in which the flaps or tongues *b* of each side are bent at 85 right angle respectively towards the right and towards the left side. By this means a uniformly ramified structure is obtained which is accordingly adapted to produce a uniform cooling action. Such bodies are 90 frequently designated as chaplets in the foundry art.

The bending of the flaps or tongues or projections *b* and *d* may obviously be effected in any other manner, so that the flaps or 95 tongues of a vertical row may for instance be alternatingly bent upon opposite sides, and the shape and length of the flaps may be different. Thus for instance and as shown in Figure 5, the flaps and tongues *b* and *d* 100

may be curved and of different lengths. The axial length of the cooling body may differ according to requirements and may correspond to the particular purposes. The cooling bodies of comparatively greater length (Figure 6) may be made without pointed ends. Along its central longitudinal axis the cooling body may be curved or bent in any desired manner in accordance with the 10 particular shape of the casting.

The cooling bodies according to this invention are inserted or introduced into the mould in the usual manner at the desired places, so that, when the liquid metal is 15 poured into the mould, the cooling bodies are thoroughly moulded thereto and produce the rapid cooling of the cast material on account of their large cooling surface and thereby obviate the occurrence of injurious tensional 20 strains within the casting. At those points where a particularly great cooling action is to be obtained the several flaps or tongues may be of comparatively longer shape and may be curved, when they are bent out of their plane 25 (Figure 5), by which means the cooling surface is increased.

While I have described and illustrated in the drawings what I consider some of the simplest and most efficient exemplifications 30 of my invention, it should be understood that my invention is not limited thereto, but it may find expression in other forms of embodiment in accordance with and within the scope of the appended claims.

35 I claim:—

1. Cooling body for foundry purposes, comprising a cross-sectionally ramified strip of sheet metal.
2. Cooling body for foundry purposes, comprising a cross-sectionally ramified and endwise pointed strip of sheet metal.
3. Cooling body for foundry purposes, comprising a cross-sectionally ramified, edge-wise curved, ramified strip of sheet metal.
4. Cooling body for foundry purposes, comprising a cross-sectionally ramified and edge-wise curved, endwise pointed strip of sheet metal.
5. Cooling body for foundry purposes, comprising a strip of sheet metal, and alternatingly and staggeringly disposed projecting flaps at the edges of the strip and bent out of its plane.
6. Cooling body for foundry purposes, comprising a strip of sheet metal and alternatingly, stepwise and staggeringly arranged sets of projecting flaps of different lengths, bent out of the plane of the strip.
7. Cooling body for foundry purposes, comprising a strip of sheet metal, a plurality of stepwise and staggeringly edge-wise arranged projecting flaps at the edges of the strip and alternatingly bent out of its plane, substantially at right angle thereof.
8. Cooling body, comprising a strip of

sheet metal, a plurality of staggeringly arranged sets of projecting flaps, alternatingly bent out of its plane, and a pointed extremity on said strip.

9. Cooling body, comprising a strip of 70 sheet metal, a plurality of staggeringly disposed projecting flaps at the edges of the strip and alternatingly bent out of its plane, curved extremities at the bent flaps, and a pointed axially extending extremity on said 75 strip.

LUDWIG FÖBUS.
